UNITED STATES PATENT OFFICE.

ALBERT C. GRUNWALD, OF CHICAGO, ILLINOIS, ASSIGNOR TO PRECISION METAL WORKERS, A CORPORATION OF ILLINOIS.

OIL-CUP.

1,386,403.

Specification of Letters Patent.

Patented Aug. 2, 1921.

Application filed October 8, 1920. Serial No. 415,483.

To all whom it may concern:

Be it known that I, ALBERT C. GRUNWALD, a citizen of the United States, residing at Chicago, in the county of Cook and State of Illinois, have invented a new and useful Improvement in Oil-Cups, of which the following is a specification.

This invention relates particularly to oil cups adapted to be applied to bearings where it is not convenient to employ forced feed.

The primary object is to provide an improved oil cup which may be readily refilled, and which is adapted to effectively exclude dust and grit.

The invention is illustrated in its preferred embodiment in the accompanying drawing, in which—

Figure 1 represents an elevational view of the improved oil cup; Fig. 2, a plan view of the same, in a closed condition; Fig. 3, a plan view of the same in open condition; Fig. 4 an inner view of the cap employed; and Fig. 5 is a detail section of the cover and upper part of the oil cup.

In the construction illustrated A represents a cup or elongated tubular member, which is provided at one end with a threaded nipple A¹, and which is equipped at the opposite end with a cap A².

The tubular body A and nipple A¹ are preferably formed integrally by drawing a steel disk into cup form, the bottom portion of the cup being contacted to form the nipple and perforated to provide a passage through which oil may pass to the bearing. In the illustration given, the cup is equipped at this lower portion with a wick B, which extends through the tubular nipple A¹.

The cap A², is preferably stamped from a disk of sheet metal. It has the upwardly dished or semispherical top portion 1 and the depending flange 1^a. The cap is provided at its apex with a central perforation 2, and at some distance therefrom with an elongated perforation or slot 3. The metal of the cap is struck outwardly at points 4, thus providing stops. Mounted on the cap is a segmental closure 5, which is curved to correspond with the curvature of the cap. The member 5 is preferably formed from sheet metal. It is provided at its apex with a perforated pivotal portion 5^a, and is provided at its periphery with a down-turned flange 5^b, which embraces the flange 1^a, the

lower edge portion of the flange 5^b being spun inwardly beneath the edge of the flange 1^a, as indicated at 5^c. The segmental closure 5 is connected with the cap at its apex by a rivet 6, which serves as a pivot for the closure. The inner end of the rivet extends through a flat spring 7, which preferably is of rectangular form. In riveting the parts together, the spring is placed under flexure, thus holding the closure tight against the top surface of the cap. At the extremities of the flange 5^b, the metal is extended and curved into cylindrical form, to provide finger pieces 8, by means of which the closure may be swung about the vertical pivot 6. The segmental closure 5 presents sharp radial edges 9, adapted to scrape the outer surface of the cap A² clean throughout the arc of movement. Such a close fit is secured by the construction employed as to effectively exclude all dust and grit from the oil cup.

The improved oil cup is adapted for use in connection with the bearings of stationary engines, in connection with the bearings for springs of automobiles, and in various other situations. The improved device is exceedingly simple in construction, capable of being manufactured at small cost and thoroughly effective for its purpose. The cup may be of convenient size to properly lubricate an ordinary bearing for a period of several weeks, without the necessity of refilling the cup in the meantime.

In the manufacture of the device, the cap and the closure applied thereto, may be assembled before applying the cap to cup A. The cap may then be forced onto the cup with a close fit, which will effectively secure it in position.

What I regard as new and desire to secure by Letters Patent, is:

1. A device of the character set forth, comprising an oil cup equipped at one end with a cap having a bowed top wall and a depending flange embracing the cup, said top wall being provided at some distance from the center with a perforation through which oil may be introduced, and a segmental closure surmounting said cap and swivelly connected therewith by a central vertical pivot, and a leaf spring engaging the inner surface of the top wall of the cap, said spring being engaged by the inner end of said pivot and held under flexure thereby.

2. A device of the character set forth, comprising an oil cup equipped at one end with a cap comprising a bowed top wall and a depending flange which embraces the upper portion of said cup, said top wall being provided with a perforation through which oil may be introduced and having a depending flange with an inturned lower edge en-

gaging the lower edge of the flange of said cap, the flange of said closure being provided with a finger piece, a leaf spring bearing against the inner surface of said cap, and an axial pivot connecting said closure to the central portion of said cap and to said spring, for the purpose set forth. 10
